ENGINE COOLING, CYLINDER, JACKET,
AND HEAD CONSTRUCTIONCharles Frank Pervier, Port Washington, Wis.,
assignor to Harnischfeger Corporation, Milwaukee, Wis., a corporation of Wisconsin

Application February 15, 1946, Serial No. 647,819

9 Claims. (Cl. 123—173)

1

This invention relates to internal combustion engine construction and resides more specifically in an assembly including a jacketed internal combustion engine cylinder with or without air admission ports such as to adapt the same for two cycle engine operation and a jacketed head, the entire assembly being so constructed as to permit its withdrawal as a unit from a crank and cylinder supporting frame to facilitate repair or replacement of parts.

Among the objects of this invention is to provide an engine construction in which a cylinder and associated head and cooling jacketing may be withdrawn as a unit without disturbing the remaining structure of the engine so as to permit repair or replacement of parts otherwise accessible only by major dismantling.

Another object of the invention is to provide an engine construction in which a separately removable cylinder assembly is held in a crank and cylinder supporting frame adapted to act not only as a support but also as an air box for maintaining air under pressure in position to enter air inlet ports in said cylinder.

Another object of the invention is to provide an engine construction in which a crank and cylinder supporting frame so engages a removable cylinder assembly as to provide an air box adjacent said cylinder assembly and a crankcase compartment below the same with a dividing partition wall between said air box and crankcase compartment, which partition wall serves as a cooling water access channel joined with cooling jacketing surrounding said cylinder assembly.

This invention is herein described by reference to the accompanying drawings forming a part hereof and in which there is set forth by way of illustration and not of limitation one form in which an engine may be constructed in accordance with this invention.

In the drawings:

Fig. 1 is an end view in elevation and partly in section of one form of engine constructed in accordance with this invention; and

Fig. 2 is an end view in elevation and in section of a fragment of the engine shown in Fig. 1 so enlarged as to more clearly depict the details of the cylinder assembly shown therein, the same being shown with the piston removed.

As shown in the drawings the form of the engine of this invention there depicted is provided with a main crank and a cylinder supporting frame designated generally by the numeral 1 which is made up of a lower crank shaft supporting portion 2 and an upwardly extending

2

cylinder supporting portion comprising interconnected side panels 3 and 4 which rise to and connect with an integrally formed head seat portion or entablature 5. The head seat 5 is vertically bored to receive the cylinder head portions of cylinder assemblies to be described in greater detail hereinafter.

Between the crank shaft supporting portion 2 and the upwardly extending panels 3 and 4 the frame 1 is provided with a horizontal chambered partition portion 6 which is bored in alignment with the bores in the head seats 5 so as to receive the lower ends of cylinder barrels of cylinder assemblies inserted through said head seat openings. The partition member 6 serves to divide the main frame 1 into a lower crankcase chamber completed by a pan 7 and an upper air box portion 8. The partition member 6 further is chambered to provide coolant passages 9 adjacent the lower ends of inserted cylinder barrels and communicating with a gallery 10 to provide access for coolant liquid.

Inserted within the bores in the entablature 5 and extending downwardly through the bores in the partition 6 are cylinder assemblies made up of a head portion 11 threadingly attached to the upper end of a tubular cylinder barrel 12 as shown more clearly in Fig. 2.

The cylinder barrel 12 is provided with a central belt or zone of substantially increased thickness 13 through which a plurality of upwardly and tangentially inclined air inlet openings 14 pass. The air inlet openings 14 are spaced apart sufficiently to permit vertically bored passages 15 to be formed between them on the exterior of the barrel 12 so as to provide passages for the transference of coolant fluid vertically through the zone 13.

Extending upwardly from the upper rim of the zone 13 to the lower part of the head 11 is a coolant jacket 16 formed of thin sheet material and secured at its lower end to the zone 13 by brazing. The upper end of the jacket 16 is provided with a rolled bead 17 adapted to engage and compress a resilient gasket 18 formed of rubber or rubber-like material reposing in a groove 19 formed in the lower part of head 11. In this way a fluid tight joint is formed between the head 11 and the upper end of jacket 16.

Extending downwardly from the zone 13 and secured to the lower edge thereof by brazing is a thin sheet metal jacket member 20, the lower edge of which is securely brazed to a coolant port ring or gland 21 having gasket engaging shoulders 22 and 23. Gasket shoulder 22 bears

against a rubber-like gasket 24 held on the upper surface of partition 6 while the shoulder 23 bears against a rubber-like gasket 25 held in a notch formed in part by a chamfered surface adjacent the bore in the lower part of the partition 6.

The ring 21 is ported radially in its lower part at 26 and vertically in its upper part at 27 so as to permit communication between the chamber 9 and the interior of the jacket 20. In this way way a separable fluid tight connection between the lower end of the cylinder assembly and the chamber 9 is provided.

As appears more clearly in Fig. 1 head 11 is provided with a series of peripherally spaced upwardly inclined coolant passages 28 extending inwardly from communication with the space enclosed by the jacket 16 to join with the several interconnected coolant chambers 29, 30, 31 and 32 formed in the head 11. The coolant passages in the head 11 in turn communicate with bypass connections 33 formed as a part of the head 11 to provide a free connection not shown with coolant chambers 34 formed in the head seat 5.

By reason of the several interconnected passages and chambers above described coolant fluid supplied through the gallery 10 after passing through the chamber 9 and ports 26 and 27 enters the space surrounding the barrel 12 enclosed by the jacket 20. Such fluid then is transferred through the passages 15 to the space enclosed by the jacket 16 surrounding the upper part of the barrel 12. From thence fluid passes through openings 28 into the chambers within the head 11 and from thence through the bypass passages 33 as indicated by dotted lines in Figure 2 into the chambers 34 in the head seat 5. From the chamber 34 fluid escapes through the cooling tube 36 from whence it is gathered by means not shown for delivery to a radiator or other medium for removal of heat.

As appears more clearly in Fig. 1 an exhaust passage 37 is formed in the head 11 back of a valve 38 and this exhaust passage registers with a corresponding passage 39 formed in the head seat 5 which in turn communicates with exhaust manifold 40.

From the foregoing description it will be apparent that the cylinder barrel 12 and associated head and jacketing form a unitary assembly which may be inserted as such in the main frame 1 and if desired, withdrawn therefrom as a unit. Provision is made for holding the cylinder assembly in place by means of a plurality of hold down bolts 41, one of which appears in Fig. 1.

Mounted upon the head 11 is a rocker arm support 42 carrying a rocker arm 43 arranged to act upon the stem of the valve 38, the latter being surrounded by valve spring 44. A fuel injector 45 is carried as shown in the head 11 in position to discharge fuel downwardly and laterally between the top of piston 46 and the bottom of valve 38.

Secured to panel 4 opposite an opening therein provided therefor is a positive displacement blower 47 adapted to supply air under pressure into the space or air box 8 surrounding the cylinder barrel 12.

In operation, air supplied to the air box 8 by the blower 47 passes forcibly through the air inlet openings 14 into the space above the piston 46 when the latter is in its lowermost position. At the same time valve 38 is maintained in open position in accordance with well known practice so that the spent charge is exhausted and a replacement charge of air enters the cylinder.

The compression stroke takes place in normal fashion followed by injection of fuel and expansion of the working charge in the cylinder during the working stroke.

By reason of the arrangement above described, when it becomes necessary to perform any repair or replacement work in connection with the cylinder head and the cylinder barrel and its associated parts it is simply necessary to remove the bolts 41 and parts auxiliary to the head 11, such as push rod 48, whereupon the entire assembly may be withdrawn as a unit. At the same time, the lower bearing cap on the connecting rod 49 may be released by access through hand holes not shown in the crank shaft chamber 2. In this way the piston 46 and rod 49 may also be removed upwardly through the main frame 1 as desired.

Head 11 by reason of its threaded attachment to the barrel 12 and by reason of the engagement of the upper end of jacket 16 with the gasket 18 may be removed from the cylinder barrel 12, thus facilitating work that may be required upon the barrel 12 or the head 11. In case a user experiences failure of a major part of the cylinder barrel assembly it is feasible for him to remove the same as a unit and return it to the factory for exchange or replacement of an identical unit which may be supplied and replaced in the engine 30 with a minimum of delay.

I claim:

1. In an internal combustion engine a main crank and cylinder supporting frame having a lower crank shaft supporting and enclosing portion and an upper cylinder supporting portion terminating at its upper end in a cylinder head seat, a chambered partition wall disposed between said upper and lower frame portions, said head seat and said chambered partition wall having aligned cylinder receiving openings therein; a head and cylinder assembly disposed in and extending through and held by said aligned openings in said head seat and said chambered partition wall, said head and cylinder assembly comprising a head portion having a coolant chamber therein, a cylinder barrel portion separably united with said head portion, and a coolant jacket surrounding said cylinder barrel portion providing a closed coolant containing chamber surrounding said cylinder barrel extending from the lower end thereof to said head portion, fluid conveying means disposed within said head seat portion joined with and providing egress for coolant from the coolant chamber in said head; and a coolant admission chamber in said chambered partition wall joined with and providing an entrance for coolant into the lower end of said jacket.

2. In an internal combustion engine a main crank and cylinder supporting frame having a lower crank shaft supporting and enclosing portion and an upper cylinder supporting portion comprising spaced enclosing members adapted to provide an air box terminating at their upper ends in a cylinder head seat and at their lower ends in a chambered partition wall dividing said air box from a crank shaft enclosing chamber within said crank shaft supporting portion, said cylinder head seat and said chambered partition wall having aligned cylinder receiving openings therein; a head and cylinder assembly disposed in and extending through and held by said aligned openings in said cylinder head seat and said chambered partition wall, said head and cylinder assembly comprising a head portion having a coolant chamber therein a cylinder barrel portion

separably united with said head portion a coolant jacket surrounding said cylinder barrel portion providing a closed coolant containing chamber surrounding said cylinder barrel and extending from the lower end thereof to said head portion; fluid conveying means disposed within said head seat portion providing egress for coolant from the coolant chamber in said head; and a coolant admission chamber in said partition wall joined with and providing an entrance for coolant into the lower end of said jacket.

3. In an internal combustion engine a main crank and cylinder supporting frame having a lower crank shaft supporting and enclosing portion and an upper cylinder supporting portion comprising spaced enclosing members adapted to provide an air box terminating at their upper ends in a cylinderhead seat and at their lower ends in a chambered partition wall dividing said air box from a crank shaft enclosing chamber within said crank shaft supporting portion, said cylinder-head seat and said chambered partition wall having aligned cylinder receiving openings therein; a head and cylinder assembly disposed in and extending through and held by said aligned openings in said cylinder-head seat and said chambered partition wall, said head and cylinder assembly comprising a head portion having a coolant chamber therein, a cylinder barrel portion having a medially disposed belt of air admission ports separably united with said head portion, an upper coolant jacket surrounding said cylinder barrel between said air admission belt and said head, a lower coolant jacket surrounding said cylinder barrel between said air admission belt and the lower end of said barrel, transfer passages through said air admission belt joining said upper and lower jackets to form a closed coolant retaining chamber surrounding said cylinder barrel and extending from the lower end thereof to said head; fluid conveying means disposed within said head seat portion joined with and providing egress for coolant from the coolant chamber in said head; and a coolant admission chamber in said chambered partition wall joined with and providing an entrance for coolant into the lower end of said lower jacket.

4. In a two-cycle reciprocating internal combustion engine having a crank shaft, a connecting rod and a piston adapted for reciprocation in a cylinder the combination comprising a crank shaft and cylinder supporting frame including a lower crank shaft support and an upper cylinder supporting air box having sides, top and bottom; said air box having aligned openings in the top and bottom thereof for admitting and supporting a cylinder; a cylinder extending through and laterally held by said aligned openings and having medially disposed air admission ports within said air box; a head for said cylinder removably anchored to and engaging the top of said air box to provide the sole anchorage against vertical movement for said cylinder; means for introducing air into said air box; and means in said cylinder head for permitting exhaust of gasses to be released from said cylinder.

5. In a two-cycle internal combustion engine having a crank shaft, a connecting rod and a piston adapted for reciprocation in a cylinder the combination comprising a crank shaft and cylinder supporting frame including a lower crank shaft support and an upper cylinder supporting air box having sides, top and bottom; said air box having aligned openings in the top and bottom thereof for admitting and supporting a cyl-

inder; a removable cylinder extending through and laterally held by said aligned openings and having medially disposed air admission ports within said air box; a head for said cylinder held in the top of said air box; means for introducing air into said air box; means in said cylinder head for permitting exhaust of gasses to be released from said cylinder; a coolant jacket mounted on said cylinder extending from the lower part thereof in communication with a coolant passage in said head; a coolant passage in the bottom of said air box in communication with the lower end of said coolant jacket; and a coolant passage in the top of said air box in communication with the coolant passage in said head.

6. In a two-cycle reciprocating internal combustion engine having a crank shaft, a connecting rod and a piston adapted for reciprocation in a cylinder the combination comprising an integrally formed crank shaft and cylinder supporting frame including a lower crank shaft support and an upper cylinder supporting air box having sides, top and bottom; said air box having aligned openings in the top and bottom thereof for admitting and supporting a cylinder; a cylinder extending through and laterally held by said aligned openings and having medially disposed air admission ports within said air box; a head for said cylinder removably anchored to and engaging the top of said air box to provide the principal anchorage against vertical movement for said cylinder; means for introducing air into said air box and means in said cylinder head for permitting exhaust of gasses to be released from said cylinder.

7. In a replaceable cylinder assembly for an internal combustion engine having a main crank shaft and cylinder supporting frame the combination comprising a tubular cylinder barrel having a medial externally disposed air port zone of increased thickness, spaced air admission ports passing radially through said zone, an upper coolant jacket united with the upper part of said air port zone and extending upwardly therefrom to a gasket engaging lip at its upper end, a chambered head threadingly attached to the upper end of said barrel and having a peripheral gasket seat adjacent the gasket engaging lip on said upper jacket, a compressible gasket disposed on said gasket seat in compressive engagement with said gasket engaging lip, coolant passages emerging from said head within the confines of said gasket seat and communicating with a chamber in said head, a lower coolant jacket united with and extending downwardly from said air port zone to coolant access openings near the lower end of said cylinder, and transfer channels extending through said air port zone transversely thereof disposed between said air admission ports and joining said upper and lower jackets.

8. In a replaceable cylinder assembly for an internal combustion engine having a main crank shaft and cylinder supporting frame the combination comprising a tubular cylinder barrel, a coolant jacket surrounding the same, a head secured to said barrel sealingly engaging the upper end of said jacket and having coolant passages therein communicating with said jacket, an external peripheral gasket seat surrounding and joined with the lower end of said jacket near the lower end of said barrel, an internal gasket seat supported by said jacket adjacent said barrel and of smaller diameter than said external seat and disposed beneath the same, and coolant passages 75 communicating with said jacket and emerging

therefrom between said internal and external gasket seats.

9. In a replaceable cylinder for an internal combustion engine having a main crank shaft and cylinder supporting frame the combination comprising a tubular cylinder barrel, a coolant jacket surrounding the same, a head secured to said barrel sealingly engaging the upper end of said jacket and having coolant passages therein communicating with said jacket, a coolant transfer gland surrounding the lower end of said barrel and joined with the lower end of said jacket, a gasket seat adapted to compressibly engage a compressible gasket peripherally disposed in an upper part of said gland, an inwardly disposed peripheral gasket seat disposed below and inwardly of said first named seat adapted to com-

pressibly engage a compressible gasket, and coolant passages in said coolant transfer gland communicating with the space enclosed by said jacket and emerging from said gland between said first and second named gasket seats.
